UNITED STATES PATENT OFFICE.

ERNEST GLASS, OF READING, PENNSYLVANIA.

TOOTHBRUSH.

1,378,781.

Specification of Letters Patent. Patented May 17, 1921.

Application filed December 26, 1919. Serial No. 347,363.

To all whom it may concern:

Be it known that I, ERNEST GLASS, a citizen of the United States, residing at Reading, in the county of Berks and State of Pennsylvania, have invented certain new and useful Improvements in Toothbrushes; and I do hereby declare the following to be a full, clear, and exact description of the invention, such as will enable others skilled in the art to which it appertains to make and use the same.

This invention relates to an improved tooth brush and one object of the invention is to provide a tooth brush having a rotatably mounted brush carrying shaft and having improved gearing for imparting rotary movement to the brush carrying shaft.

Another object of the invention is to so construct the gearing that the main drive gear may be rotated through the medium of a tape when the brush is moved in one direction and through the medium of a resilient spring element when the brush is moving in an opposite direction, the main drive gear at all times rotating in one direction.

Another object of this invention is to so construct this gearing that the direction of rotation of the brush shaft may be readily controlled. It has been found that teeth should be brushed from the gums toward the biting edges or faces and this construction will prevent the brush from rotating in a direction from the biting edges of the teeth toward the gums.

This improved tooth brush is illustrated in the accompanying drawings, wherein:

Figure 1 is a side elevation of the improved brush.

Fig. 2 is a vertical sectional view of the improved brush.

Fig. 3 is a view showing the brush in top plan, the gear housing being shown in section on the line 3—3 of Fig. 2.

Fig. 4 is an enlarged elevation of the gearing.

Fig. 5 is a section taken on the line 5—5 of Fig. 2.

Fig. 6 is an enlarged sectional view showing the manner of connecting the brush head with the brush shaft, and

Fig. 7 is a section taken on the line 7—7 of Fig. 6.

This improved brush is provided with a housing 10 which will be known as a gear housing or handle and a shaft housing 11

which extends from the upper portion of the gear housing at one side thereof and is braced by the diagonally extending brace 12. The brush shaft 13 is rotatably mounted in the shaft housing 11 and extends beyond its outer end thereof with its outer end portions reduced and carrying a brush head 14 the inner ends of which is flattened as shown at 15 and fits into the slotted end portion 16 of the shaft. A securing nut 17 is screwed upon the threaded end portion of the reduced outer end of this shaft and engages the brush head so that the brush head will be securely held in place and turned with the brush shaft.

The main driving gear 18 is loosely mounted upon a vertically extending shaft 19 positioned in the gear housing and rotatably mounted therein and this main drive gear 18 is engaged by the beveled pinions 20 and 21 loosely mounted upon the inner end portion of the brush shaft 13 upon opposite sides of the main drive gear so that these pinions rotate in opposite directions upon the brush shaft. A clutch sleeve 22 which is slidably mounted upon the brush shaft between the pinions and limited in its sliding movement and held against rotation upon the brush shaft by the pin 23 which extends through the slot 24 of the sleeve, is provided with a collar 25 engaged by a shifting key 26 slidably mounted in the head of the gear housing so that the clutch sleeve may be selectively brought into engagement with the pinions 20 and 21 and thus the direction of rotation of the brush shaft controlled. A shaft 27 is positioned horizontally in the gear housing and supported from the wall of the housing and also by the bearing 28 through which the shaft 19 extends and carries a gear 29 which meshes with the gear 18 and also meshes with the power element for actuating the gear 30 which gear is slidably mounted upon the shaft 19 and is provided with a hub extending beneath the gear and terminating in a reduced end portion 32 having an inclined slot 33 formed therein to receive the pin 34 of the shaft. This hub 31 has a tape 35 wound upon it and the tape extends through an opening formed in the gear housing so that the tape may be releasably connected with a hook or other similar device secured in a wall. A spring 36 is coiled about this hub with its inner end connected with the hub and has its outer end portion

extended and connected with the wall of the gear housing so that when the tape is drawn outwardly thus rotating the gear, the spring will be wound upon the hub. Therefore 5 when strain upon the tape is released the spring will uncoil thus rotating the gear in the opposite direction.

When this tooth brush is in use the tape will be connected with a hook or other permanent 10 member and the brush will be used in the usual manner. As the brush is moved back and forth along the teeth the brush shaft will be rotated and the brush turned with the bristles moving from the gums toward the biting edges or faces of the teeth, 15 the upper teeth of one side and the lower teeth of the second side will first be brushed and the latch 26 will then be moved to cause the shaft to rotate in an opposite direction and the upper teeth of the second side and lower teeth of the first side will 20 then be brushed. As the brush is moved to draw the tape outwardly a gear 30 will be rotated and since the slot 33 is cut at an incline as shown, the gear will be moved 25 along the shaft 19 and into engagement with the gear 29. This gear 29 will thus be rotated and through the medium of this gear 29 rotary movement will be transmitted 30 to the main gear 18 with which the pinions 20 and 21 mesh. As this gear 18 rotates the clutch teeth 37 will slip past the teeth of the clutch 38 loosely mounted upon the shaft 19 and held against rotation there- 35 on by pin 39 and yieldably held in engagement with the teeth 37 by a spring 40. When the brush is moved to relieve the tape from the pulling strain the spring will unwind and in doing so will rotate the gear 40 30 in an opposite direction to that in which it was previously rotated and will of course wind the tape upon the hub. As the gear 30 rotates in the second direction the gear will move out of engagement with the gear 45 29 and upon the pin reaching the end of the slot 33 continued rotation of the gear will cause the shaft 19 to be rotated. The teeth of the clutch element 38 carried by the shaft will then have operative engage- 50 ment with the clutch teeth 37 thus causing the gear 18 to continue rotation in the same direction. It will thus be seen that this brush is so constructed that the gear 18 will have continued rotation in the same direction 55 without regard to whether the gear 30 is rotated under action of the tape 35 or spring 36.

What is claimed is:—

1. A device of the class set forth comprising a rotary brush, a shaft carrying the brush, a support common to said brush and said shaft and adapted in the use of the device to be manipulated to reciprocate the brush, a driving element rotatably carried by the support, means adapted to be actuated by the manipulation of the support to rotate said driving element in reverse directions alternately, and means carried by said support through which the alternate reverse rotations of said driving element impart a continuous one-way rotary movement to said shaft. 60 65

2. A device of the class set forth comprising a rotary brush, a shaft carrying the brush, a support common to said brush and said shaft and adapted in the use of the device to be manipulated to reciprocate the brush, a driving element rotatably carried by the support, means adapted to be actuated by the manipulation of the support to rotate said element in reverse directions alternately, means carried by said support through which the alternate reverse rotations of said driving element impart a continuous one-way rotary motion to said shaft, 70 75 80

3. A device of the class set forth comprising a rotary brush, a shaft carrying the brush, a support common to said brush and shaft and adapted in the use of the device to be manipulated to reciprocate the brush, a driving element rotatably carried by the support, means adapted to be actuated by the manipulation of the support to rotate said element in reverse directions alternately and consisting of a spring connected to said support and said driving element and coiled about the latter and a pull tape connected to said driving element and coiled about the same in a direction reverse to the direction in which the spring is coiled about said driving element, and means carried by said support through which the alternate reverse rotations of said driving element impart a continuous one-way rotary movement to said shaft. 90 95 100 105

In testimony whereof I affix my signature in presence of two witnesses.

ERNEST GLASS.
